UNITED STATES PATENT OFFICE.

FREDERICK W. BARNES, OF ROCHESTER, NEW YORK, ASSIGNOR TO EASTMAN KODAK COMPANY, OF ROCHESTER, NEW YORK, A CORPORATION OF NEW YORK.

DEVELOPING-RACK.

1,339,088.

Specification of Letters Patent.

Patented May 4, 1920.

Application filed January 11, 1919. Serial No. 270,740.

To all whom it may concern:

Be it known that I, FREDERICK W. BARNES, a citizen of the United States of America, residing at Rochester, in the county of Monroe and State of New York, have invented certain new and useful Improvements in Developing-Racks, of which the following is a full, clear, and exact specification.

10 My present invention relates to photographic apparatus and more particularly to holders for cut film sheets during development, fixing, washing and drying, or such other treatments as may be desired, and its 15 object is to provide a simple, light and efficient holding frame to maintain them flat during the operations mentioned.

Reference is made to the accompanying drawings in which:

20 Figure 1 is a perspective view of a film rack with the film positioned therein;

Fig. 2 is a perspective view of the inner frame;

25 Fig. 3 is a fragmentary section showing only one side bar of the rack and frame with a film clamped therein;

Fig. 4 is a similar section on the line 4—4 of Fig. 2;

30 Fig. 5 is a fragmentary view showing a clamp struck up from the body of the material, forming the inner frame;

Fig. 6 is a similar view showing a clamp made from a separate piece of material.

35 In all of the figures the same reference characters indicate the same parts.

The rack comprises two frames, the outer frame having a crossbar 1 the ends of which extend beyond the edges of the frame to form a suspending means, whereby the rack 40 as a whole may be supported in a suitable tank. From this bar two side bars 2 extend downwardly. These have overhanging flanges 3 extending from the bottom nearly to the top. A lower cross-bar 4 connects

45 the bottom ends of these two side bars. This outer frame is substantially the same as that disclosed in the patent to Grubman, No. 1,019,320, issued March 5, 1912, and one of the objects of my invention 50 is to provide a second frame to be used with this frame, so that the owners of frames of this type may employ them for the development both of plates and cut films.

The second or inner frame is rectangu-

lar in shape and comprises a top crossbar 55 having a manipulating handle 6, a bottom crossbar 16, which may have apertures 17 therein, and side bars 7 with overhanging flanges 8. Struck from the material of these overhanging flanges are resilient 60 clamps 9 terminating in inwardly facing jaws 10 which may have points 12 thereon to engage the film 11 and press it against bar 7 in which suitable apertures 13 may be made to accommodate the points of the jaws. 65 If desired, as shown in Fig. 6, the material of this spring may be made of a separate piece of metal 9' having a bent jaw 10', in which case an aperture 14 is made in flange 8. The separate piece of material is attached to the flange by rivets 15. This permits the use of resilient material of better quality than the rest of the frame for the spring jaws.

In operation, the inner frame is laid flat 75 upon any suitable surface and the film slid into the frame until its edge contacts with the bar 16. The inner frame, as a whole, is then slid into the grooved outer frame, and the rigid walls of the side bars of this outer 80 frame will force the resilient arms 9 inwardly and cause the points 12 of the clamps to engage the film 11 as the inner frame is slid into place. When the bar 16 contacts with the bar 4, the film will be securely held 85 in position and the rack as a whole will then be placed in a suitable developing tank and the usual operations performed upon it.

While I have shown a specific embodiment 90 of my invention, it will be understood that I contemplate in the construction thereof changes, such as the particular shape and location of the clamps and any other modifications falling within the scope of the following claims.

Having thus described my invention, what I claim as new and desire to secure by Letters Patent is:

1. A frame consisting of end bars and side bars, the latter having inwardly turned 100 grooves, resilient clasping jaws mounted on one wall of the grooves and adapted to clamp sheet material against the other wall of the groove.

2. A frame consisting of end bars and side bars, the latter having inwardly turned 105 grooves, each of said side bars carrying a clasping jaw having a resilient support ex-

tending lengthwise of said side bars, and means slidably related to the side bars adapted to actuate and to maintain in gripping position said jaws.

5 3. A rack for supporting a sheet of flexible material, comprising a frame, clamps on the sides of the frame, and a second frame having grooved sides, the grooved sides of the second frame being adapted to embrace 10 and operate the clamps of the first frame, whereby they may grip the edges of a flexible sheet.

15 4. A rack for supporting a sheet of flexible photographic material, comprising a rectangular frame, the sides of which are flanged, resilient clasping jaws on the flanged sides, and a second rectangular frame having grooved sides in which the first frame fits, the grooved sides of the second frame embracing the grooved sides of the first frame and operating the jaws.

20 5. A rack for supporting a sheet of flexible material, comprising a frame with grooved sides, the grooves being open at one end, a second frame with clamps on it, the second frame fitting within said grooves and adapted to be slid therein through the open end thereof, the walls of the groove when thus embracing the second frame op-

erating the clamps, whereby they may grip 30 the edges of a flexible sheet.

6. A rack for supporting a sheet of material, comprising a frame having means by which it may be suspended and sides with inwardly facing grooves, and a second frame 35 adapted to fit within the grooved sides, the second frame having side grooves within which the edges of a flexible sheet may be laid, and spring jaws to grip such edges, the jaws being held in gripping position by 40 the first named frame.

7. A rack for supporting sheets of flexible photographic material, comprising a frame having suspending means, and parallel sides with inwardly facing grooves, the grooves 45 being open at one end, and a second frame having parallel sides with inwardly facing grooves, and resilient jaws mounted on one wall of such grooves and adapted to press against the other wall, the second frame fitting within and adapted to be slid within the grooves of the first frame through the open ends thereof, whereby the jaws will be held in gripping position.

Signed at Rochester, New York, this 6th 55 day of January, 1919.

FREDERICK W. BARNES.
